Filed Mar. 25, 1971, Ser. No. 128,207

Term of patent 14 years

Int. Cl. D6—03

U.S. Cl. D6—177

FIG. 1

FIG. 2

FIG. 3

FIG. 1 is a perspective view of the low table of the invention;

FIG. 2 is a top view of the low table of the invention; and

FIG. 3 is a side view of the low table of the invention.

The design is characterized by a combination of features on the table disclosed which create a heavy, squat appearance; the features comprising a thick, rectangular surface member and four straight, stubby legs which have unusually large diameters relative to the height and size of the surface member, and which extend through the surface member so that their top ends are exposed at the top of the surface member.

I claim:

The ornamental design for a low table, as shown and described.
